INVENTOR,

Benedict B. Lederer

BY Horatio E. Billows ATT'y.

UNITED STATES PATENT OFFICE.

BENEDICT B. LEDERER, OF PROVIDENCE, RHODE ISLAND.

HAIR-FASTENER.

SPECIFICATION forming part of Letters Patent No. 662,949, dated December 4, 1900.

Application filed September 7, 1900. Serial No. 29,271. (No model.)

To all whom it may concern:

Be it known that I, BENEDICT B. LEDERER, a citizen of the United States, residing at Providence, in the county of Providence and State of Rhode Island, have invented a certain new and useful Improvement in Hair Clasps or Brooches, of which the following is a specification, reference being had therein to the accompanying drawings.

My invention relates to that class of hair ornaments and brooches which are retained in place by means of pin-tongues, and particularly to those pins having a body or face composed of frangible material, such as pearl, celluloid, horn, &c.

The clasps now in use resemble ordinary brooch-pins, and their structure presents numerous projections and interstices whereby the hair is accidentally engaged, torn, and tangled.

My device has for its object the correction of these evils; and to that end it consists in the novel construction and arrangement of parts illustrated in the accompanying drawings, wherein—

Figure 1 is a back elevation of my new clasp; Fig. 2, a vertical transverse section of the same on line $x-x$, Fig. 1; Fig. 3, a transverse section of the same on line $z-z$, Fig. 1. Fig. 4 is a plan of the inclosing shell; Fig. 5, a plan of the shell with pin-tongue engaged; Fig. 6, a like view with inserted spring, and Fig. 7 a plan of the completed pin and joint ready for attachment to the clasp-body.

In the drawings like letters of reference refer to like parts throughout.

The construction of my pin is as follows: A clasp-body A of any desired design or material is selected, but preferably of pearl, which is transversely pierced in three places $a a'$ for the insertion of pins. The pin and joint parts are next constructed and assembled as follows: An inclosing shell C is struck up out of thin metal, having its bottom pierced with two small holes c and a rectangular opening d , the latter flanked by rectangular depressions e on either side to form a bearing for the end of the pin-tongue. Other less pronounced depressions $b b$, stamped herein, are found to facilitate the action of the parts. The pin-tongue B consists of a broad body with an abruptly-tapering point i , pierced

with a hole o , having a T-shaped end m , rectangular in cross-section, which serves as an axis for the pin-tongue. The pin-tongue member is next engaged with the inclosing shell, as shown in Fig. 5, with its axial end m resting in the bearings e . A flat spring n is next laid over the parts thus assembled, Fig. 6, and the upright wall of the inclosing shell C is rolled over inwardly and bears upon the face of the spring, thus retaining the latter in place, Fig. 7. The parts thus assembled are attached to the clasp-body thus: The inclosing shell C, with its attached parts, is placed upon a convenient part of the clasp-body A. Pins r are passed through the openings a of the body A and the openings c of the shell C, with their heads s abutting upon the clasp-body and their ends projecting slightly above the shell C. Over each of these projecting pin ends is applied a small tube t , which is united with the pin projection by solder dropped into the annular space between the tube and pin. I next pass a file across the exposed ends of the tubes and pins to bring them more nearly flush with the inclosing shell.

The point of the pin-tongue is protected from lateral displacement by a pin v passing through the openings a' of the body and o of the pin-tongue and held in position by the washer w .

The clasp thus constructed presents no obnoxious projections, relieves a delicate body or face of all strain, and has a positive tongue action.

Having thus described my invention, what I claim as new, and desire to secure by Letters Patent, is—

1. A hair clasp or brooch, consisting of a body, an inclosing shell with rectangular bearings, a pin-tongue having a T-shaped base rectangular in cross-section mounted in said bearings, a pin projecting from the back of the clasp-body adapted to register with an opening in the pin-tongue, the said shell inclosing the bearing and pivot of the tongue, as set forth.

2. In a hair clasp or brooch, the combination of a body, an inclosing case attached to said body, a pin-tongue capable of positive action mounted in bearings in said case, a pin projecting from the back of the clasp-body and adapted to register with an opening in

the pin-tongue, and tubes inclosing the pins which secure the case to the body, as and for the purpose specified.

3. The hair clasp or brooch herein described consisting of a body of frangible material, an inclosing shell attached to said body, pins for securing said parts together, tubes inclosing said pins, a pin-tongue mounted in bearings within said shell, and a spring placed over the

pivot of the pin and held by said shell, all substantially as shown and described.

In testimony whereof I have affixed my signature in presence of two witnesses.

BENEDICT B. LEDERER.

Witnesses:
